DOOR OPENER

John D. Strobell, New Haven, Conn., assignor to
The Safety Car Heating and Lighting Company,
Inc., a corporation of Delaware

Application February 20, 1940, Serial No. 319,843

16 Claims. (Cl. 260—153)

This invention relates to door operating apparatus and more particularly to an automatic device for opening and closing a door or the like.

One of the objects of my invention is to provide door operating apparatus which is simple, compact and sturdy in construction, and which is characterized by a large ratio of power output to power input. Another object is to provide apparatus of the above nature which is serviceable over an extended period, without need of adjustment or repair. Another object is to provide apparatus of the above nature capable of being used in a limited space. Other objects will be in part apparent, and in part pointed out hereinafter.

The invention accordingly consists in the features of construction, combinations of elements, and arrangements of parts as will be exemplified in the structure to be hereinafter described, and the scope of the application of which will be indicated in the following claims.

In the drawings, wherein there is shown one embodiment of my invention,

Figure 1 is a perspective view of a door having my operator applied thereto;

Figure 2 is a top plan view of my door operator;

Figure 3 is a front elevation of my door operator;

Figure 3A is an enlarged fragmentary sectional elevation of a portion of my door operator;

Figure 4 is a sectional elevation taken along the line 4—4 of Figure 3;

Figure 5 is an enlarged fragmentary horizontal section of a portion of my operator;

Figure 6 is an enlarged fragmentary sectional elevation of a portion of my operator;

Figure 7 is a wiring diagram of the control circuit for my operator; and

Figure 8 is a section taken along the line 8—8 of Figure 5.

Similar reference characters refer to similar parts throughout the various views of the drawings.

To facilitate a clearer understanding of certain aspects of my invention, it might here be pointed out that door operators of the character under consideration are often so complicated and bulky as to preclude their practical commercial use. Others require such excessive power input as to be uneconomical in many respects. Still others are of such a character that their installation is limited to certain ideal conditions or require such constant attention and adjustment that they are a source of trouble rather than a convenience. It is accordingly another object of this invention to

provide an automatic door opener which obviates the above conditions, in addition to others.

Referring to Figure 1, a door 10 is hingedly mounted on a wall or casing 11 for swinging movement relative to an opening therein below a ceiling 14. Movement of the door is effected by an operator generally indicated at 12 secured to wall 11 and hydraulically actuated by a pump unit generally indicated at 13 located above ceiling 14. It should be noted, however, that a number of variations in the location of operator 12 and pump unit 13 are possible without departing from the scope of my invention, and accordingly the locations thereof as shown in Figure 1 are to be considered as illustrative only. For example, operator 12 may be secured directly to door 10, or may be located above ceiling 14. Similarly, pump unit 13 may be located adjacent to or distant from operator 12, as desired, or as dictated by available installation space or other factors.

With reference to Figure 2, operator 12 includes a housing 15 which is preferably an integral casting, and which has formed on the rear thereof an attaching plate 16 provided with suitable screw holes 17 by which the housing may be secured to door 10 (Figure 1) see also Figure 4. In the right-hand end of housing 15, as viewed in Figure 2, I provide a cylinder 18 in which is reciprocably disposed a piston rod 19, on the right-hand end of which is secured a piston 20. The left-hand end of rod 19 is disposed in a guide 21 suitably secured in the left-hand end of housing 15. The left-hand end of guide 21 is preferably closed by a suitable screw cap 22 or the like.

Still referring to Figure 2, the right-hand end of cylinder 18 is closed by a cap 23 or the like, through which a pipe fitting 24 extends to supply fluid to the cylinder. A pipe 25 is secured to fitting 24 and leads to pump unit 13 (Figure 1). From the above, it may now be seen that fluid under pressure may flow through pipe 25 and the cylinder 18 to force piston 20 and accordingly rod 19 to the left. Movement of piston rod 19 beyond a predetermined point automatically shuts off pump unit 13 (Figure 1) so that the piston rod and piston may return to the position shown in Figure 2, all as will be described in greater detail hereinafter.

As shown in Figure 2, housing 15 includes a drum-shaped casing 26 or the like which is preferably integral with housing 15 and communicates interiorly therewith (see Figure 4). A ball bearing 27 is mounted in a boss 28 extending upwardly from the bottom of casing 26, and in this bearing is rotatably disposed a shaft 29. A pack-

ing gland 30 surrounding shaft 29 lies between the bottom of bearing 27 and the bottom of casing 26 so as to preclude leakage of lubricant from the casing. Gland 30 is preferably spaced from bearing 27 and held in operative position by a washer 31 lying between the outer race of the bearing and the top of the gland.

A flanged drum 32 is secured to shaft 29 so as to rotate therewith and on the flange of this drum is secured a ring gear 33 as by screws 34 or the like. The teeth on ring gear 33 mesh with teeth 19a formed on piston rod 19, the piston rod accordingly constituting a rack, reciprocation of which effects rotation of drum 32 and accordingly shaft 29. The upper end of shaft 29 is preferably reduced and is journaled in a ball bearing 35 housed in a suitable boss 36 formed in a cover or cap 37 adjustably mounted on the top of casing 26. Cover 37 is held in place by a rabbeted washer or ring 38 secured to the top of casing 26 as by screws 39. Thus, it may be seen that the upper and lower ends of shaft 29 are effectively supported within casing 26 for rotation therein. It may also be seen that casing cover 37 is rotatable relative to the casing, and this for a purpose which will be described hereinafter.

Drum 32 is provided with an annular recess 40, cover 37 also including an annular recess 41 which registers with recess 40 when the cover is in place. Recesses 40 and 41 house the opposite ends of a torsion spring 42, the lower end 42a of which is secured in any suitable manner to drum 32, and the upper end 42b of which is suitably secured to cover 37. Accordingly, rotation of the cover relative to casing 26 adjusts the tension of spring 42.

As is more clearly shown in Figure 2, the top of cover 37 is provided with a suitable number of notches 43 or the like, any one of which may receive a pawl 44 pivoted as at 45 to casing 26. Hence when cover 37 is rotated in such a direction as to tension spring 42, the cover may be held in its adjusted position by the insertion of pawl 44 in one of notches 43. With cover 37 so held, spring 42 (Figure 4) is tensioned so as to bias drum 32, and accordingly shaft 29, in a clockwise direction (as viewed in Figure 2) which is the door closing direction of operation of shaft 29.

As shown in Figure 4, the lower end of shaft 29 is preferably squared so that the bifurcated end of a door swinging rod 46 may be clamped thereabout as by a nut and bolt 47. The free end of rod 46 has a pin or stud 48 (Figure 3A) secured thereto and extending downwardly therefrom, the bottom of this stud being provided with a stop 49. Stud 48 carries a roller generally indicated at 50 which is free to turn thereon, and this roller preferably comprises an inner sleeve 51 and an outer sleeve 52. As is better shown in Figure 2, a guide 53 or the like is secured to door 10, roller 50 being disposed in the guide and acting on the vertical parallel surfaces thereof to transmit the motion of arm 46 to door 10.

From the above, it will now appear that upon flow of fluid under pressure into cylinder 18 (Figure 2) piston rod or rack 19 effects counterclockwise movement of drum 32 (Figure 4) and accordingly shaft 29. This, in turn, causes counterclockwise movement of door rod 46 (Figure 2) which opens the door. During door opening operation of drum 32 (Figure 4) spring 42 is tensioned by reason of the relative movement between the drum and cover 37. Hence, the door

may be automatically closed by the stored energy in spring 42 upon cessation of power input to operator 12.

With reference to Figure 1, pump unit 13 includes a pump 54 and an operating motor 55. Motor 55 (Figure 7) is connected to a source of current 56 by a pair of lines 57 and 58, in the latter of which is a relay controlled switch 59. A switch generally indicated at 60 is located in operator 12 (Figure 5) and one terminal 61 of this switch (see Figure 7) is connected by a line 62 to line 58 and accordingly to one side of source 56. The other terminal 63 of the switch is connected by a line 66 to one side of a relay 64. The other side of relay 64 is connected by a line 65 to line 57, and accordingly to the other side of source 56. When relay 64 is energized switch 59 is closed, which closes the circuit to motor 55 to effect energization thereof to drive pump 54 (Figure 1). The pump forces fluid under pressure through pipe 25 into operator 12, as hereinbefore described, to open door 10. When the door approaches its open position, switch 60 (Figure 7) is automatically opened, as will be described in detail hereinafter, which breaks the circuit to relay 64, causing switch 59 to open and accordingly motor 55 to stop. This shutting off of the power input into operator 12 (Figure 1) permits spring 42 (Figure 4) to close the door, as described.

Referring back to Figure 7, a door or wall switch generally indicated at 67 may be connected across lines 62 and 66, and closing thereof has the same starting effect on the operator as does closing of switch 60. As will be later pointed out, however, switch 60 is held closed automatically for the larger portion of opening operation of the operator, and hence opening of door or wall switch 67 subsequent to initial operation of the operator is ineffective to stop the operator.

Referring now to Figure 6, operator switch 60 is bolted to a panel 68 depending from a frame or the like generally indicated at 69. As is more clearly shown in Figure 5, frame 69 includes front and rear walls 70 and 71 respectively, and through these walls extends a stud 72 or the like secured to a partition 73 in housing 15. Stud 72 has a head 74 sufficiently spaced from a collar 75 near the other end of the stud to provide sufficient clearance for pivotal movement of frame 69 about the axis of the stud.

Through the right-hand end of frame 69, as viewed in Figure 5, extends a stud 76 (Figure 8) on which a roller 77 is rotatably mounted. A pair of friction discs 78 and 79 are fixed to stud 76 on opposite sides of roller 77, and these discs are clamped about the roller by a bushing 80 keyed on stud 76 and biased axially toward the discs by a spring 81. Spring 81 is held in position on the free end of stud 76 by a nut and washer 82. An arm 83 is secured to bushing 80 and hence rotates with stud 76. A spring 84 is coiled about bushing 80 and has one end 85 secured to arm 83, and its other end 86 secured to wall 70 of frame 69, spring 84 being so tensioned as constantly to bias arm 83 counterclockwise as viewed in Figure 6.

The periphery of roller 77 is preferably milled or knurled and this surface rides on the upper surface of piston rod or rack 19 (Figure 6) which is similarly milled. The right-hand end of frame 69, as viewed in Figure 6, has secured thereto a small bracket 87 or the like which supports a stud 88 about which a spring 89 is dis-

posed. The upper end of spring 88 bears against the top of housing 15, and its lower end bears against bracket 87, the spring being of sufficient length to bias frame 69 clockwise about stud 12. This bias of the frame firmly engages the milled surface of roller 77 and piston rod 19 so that movement of the rod imparts rotation to the roller.

When rod 19 moves to the left, as viewed in Figure 5, roller 77 is rotated clockwise, as viewed in Figure 6. As the roller is clamped between friction discs 78 and 79 (Figure 5) the discs are rotated by the roller, and shaft 76 is rotated. This rotation effects clockwise movement of arm 83 (Figure 6) causing the arm to bear against a switch button 90 to close the contacts of switch 60. The clockwise movement of arm 83 is, of course, limited by the extent of movement of which button 90 is capable, and hence continued movement of rack 49 in the direction of the arrow merely causes slippage between roller 77 and friction discs 78 and 79 (Figure 5).

Piston rod 19 (Figure 6) is provided with a notch 91 or the like, which is so positioned as to ride under roller 77 when the piston rod nears its limit of door opening travel. When notch 91 underrides roller 77, the milled surface of the roller is freed from the milled surface of rod 19, and the bias of spring 84 (Figure 5) is accordingly free to cause counterclockwise movement of arm 83 (Figure 6) which lifts the arm from switch button 90 to cause switch 60 to open. This counterclockwise movement of arm 83 is, however, limited by an adjustable stop 92 secured to wall 70 of frame 69.

It may now be seen, with reference to Figures 5, 6 and 7, that automatic operation of the door operator may be instigated by an initial, slight, manual opening of door 40, or by manual operation of door switch 67 (Figure 7) sufficient to move piston rod 19 to the left (Figure 5) so that the rod may rotate roller 77 sufficiently to cause arm 83 (Figure 6) to close the contacts in switch 60. When this occurs, pump motor 55 (Figure 7) is energized, as hereinbefore described, and the door continues to open automatically. When the door nears the limit of its opening movement, notch 91 in rod 19 (Figure 6) underrides roller 77, arm 83 moves counterclockwise (Figure 6) as hereinbefore described, this movement of the arm permitting the contacts in switch 60 (Figure 7) to open. This, of course, deenergizes motor 55, and the door is free to close by reason of the bias of spring 42 (Figure 4).

It may accordingly be seen that regardless of the position of the door, the operator immediately reacts to a manual impulse imparted to the door regardless of the direction of the impulse with respect to the opening or closing direction of movement of the door. Hence if the door is given a slight opening movement, the operator will continue the opening movement and automatically stop operation of the pump unit when the door is fully opened. If the door is closing and is in any position, a light push on the door in opening direction will effectuate the operator. Similarly, if the door is opening and in any position, a light push on the door in closing direction reacts on the operator similarly to the underriding of roller 77 (Figure 5) by piston notch 91, i. e. arm 83 is raised from switch 90 by spring 84.

To adjust the point at which the operator is automatically deenergized, frame 69 (Figures 5 and 6) is adjustable longitudinally of piston rod 19 so as to vary the point in the travel of the rod

at which its notch 91 underrides roller 77. To this end a plate 93, having a slot 94 in the right-hand end thereof (Figure 6) is adjustably secured to front wall 70 of frame 69. A stud 95 (Figure 5) extends through wall 70 and through slot 94 (Figure 6) in plate 93 and carries a lock washer 96, which may be clamped against the front of plate 93 by a nut 97 threaded on the outer end of stud 95. The left-hand end of plate 93 (Figure 5) is secured to stud 12 so as to be immovable relative thereto, except pivotally. Walls 70 and 71 of frame 69 have elongated slots 98 and 99 formed therein and stud 72 (Figure 5) extends through these slots. Hence, when nut 97 and lock washer 96 are loosened, walls 70 and 71 of frame 69 may be moved relative to plate 93 as the plate may slide relative to stud 95 and walls 70 and 71 may slide relative to stud 72, hence permitting adjustment of frame 69 longitudinally of piston rod 19. Thus, roller 77 may be positioned, as desired, with respect to notch 91 (Figure 6) in rod 19.

It may now be seen that I have provided an automatic door operator which attains the several objects hereinbefore set forth in a thoroughly practical and efficient manner.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. A limit switch for a cyclically operating mechanism including a member operable in opposite directions for each cycle of operation of the mechanism, said switch comprising, in combination, a casing associated with said member, a frame pivotally mounted in said casing adjacent said member and movable toward and away from said member, a roller rotatably mounted in said frame and adapted to engage said member for rotation thereby in one direction or the other as said member moves, a switch mounted in said casing adjacent said roller, means operated by said roller during rotation thereof in one direction for closing said switch, and a spring operatively associated with said switch closing means for biasing said switch closing means in switch opening direction whereby said switch opens upon rotation of said roller in the opposite direction.

2. A limit switch for a cyclically operating mechanism including a member operable in opposite directions for each cycle of operation of the mechanism, said switch comprising, in combination, a casing associated with said member, a frame pivotally mounted in said casing adjacent said member and movable toward and away from said member, spring means for biasing said frame toward said member, a roller rotatably mounted in said frame and adapted to engage said member for rotation thereby in one direction or the other as said member moves, a switch mounted in said casing adjacent said roller, means operated by said roller during rotation thereof in one direction for closing said switch, and a spring operatively associated with said switch closing means for biasing said switch closing means in switch opening direction whereby said switch opens upon rotation of said roller in the opposite direction.

3. A limit switch for a cyclically operating mechanism including a member operable in opposite directions for each cycle of operation of the

mechanism, said switch comprising, in combination, a casing associated with said member, a shaft rotatably mounted in said casing adjacent said member, a roller rotatably mounted on said shaft and adapted to engage said member to be rotated in opposite directions thereby upon operation thereof, clutch means associated with said shaft and said roller and operable to effect a driving relationship between said roller and said shaft whereby rotation of said roller causes rotation of said shaft, a switch mounted in said casing adjacent said roller, and means connected to said shaft so as to be rotated thereby and operatively associated with said switch for closing said switch upon rotation of said roller in one direction and for opening said switch upon rotation of said member in the opposite direction.

4. A limit switch for a cyclically operating mechanism including a member operable in opposite directions for each cycle of operation of the mechanism, said switch comprising, in combination, a casing associated with said member, an element rotatably mounted in said casing and adapted to engage said member for rotation in opposite directions thereby, a clutch disc rotatably mounted in said casing adjacent said element, spring means for urging said disc against said element to be driven thereby, an arm connected to said clutch disc and movable in one direction or the other depending upon the direction of rotation of said element, and a switch mounted in said casing adjacent said arm and closable and openable thereby depending upon the direction of operation thereof.

5. A limit switch for a cyclically operating mechanism including a member operable in opposite directions for each cycle of operation of the mechanism, said switch comprising, in combination, a casing associated with said member, an element rotatably mounted in said casing and adapted to engage said member for rotation in opposite directions thereby, a clutch disc rotatably mounted in said casing adjacent said element, spring means for urging said disc against said element to be driven thereby, an arm connected to said clutch disc and movable in one direction or the other depending upon the direction of rotation of said element, a switch mounted in said casing adjacent said arm and closable and openable thereby depending upon the direction of operation thereof, and spring means for biasing said arm in switch opening direction.

6. A limit switch for a cyclically operating mechanism including a member operable in opposite directions for each cycle of operation of the mechanism, said switch comprising, in combination, a casing operatively associated with said member, an element rotatably mounted in said casing in frictional engagement with said member and adapted to be rotated in one direction or the other thereby except when in juxtaposition to a notch formed in said member, a switch mounted in said casing adjacent said element and including a closing and opening button, means operatively associated with said element for pressing said switch button to its closed position during rotation of said element in one direction, and a spring for biasing said means away from said switch button when said element and notch are juxtaposed to open said switch.

7. A limit switch for a cyclically operating mechanism including a member operable in opposite directions for each cycle of operation

of the mechanism, said switch comprising, in combination, a casing operatively associated with said member, an element rotatably mounted in said casing in frictional engagement with said member and adapted to be rotated in one direction or the other thereby except when in juxtaposition to a notch formed in said member, a switch mounted in said casing adjacent said element and including a closing and opening button, means operatively associated with said element for pressing said switch button to its closed position during rotation of said element in one direction, a spring for biasing said means away from said switch button when said element and notch are juxtaposed to open said switch, and means for varying the position of said element and said switch relative to said notch to control at will the time of switch opening by reason of the juxtaposition of said element and said notch.

20 8. A limit switch for a cyclically operating mechanism including a member operable in opposite directions for each cycle of operation of the mechanism, said switch comprising, in combination, a casing operatively associated with said member, an element rotatably mounted in said casing in engagement with said member and adapted to rotate in one direction or the other depending upon the direction of operation of said member, a switch mounted in said casing adjacent said element, an arm pivotally mounted in said casing in operative association with said switch and movable in one direction relative thereto to close said switch and in another direction to open said switch, said rotatable element comprising a clutch member, and a second clutch member connected to said arm and engageable with said first-mentioned clutch member for moving said arm in switch closing direction upon rotation of said element in one direction and for opening said switch upon rotation of said element in the opposite direction.

25 9. A limit switch for a cyclically operating mechanism including a member operable in opposite directions for each cycle of operation of the mechanism, said switch comprising, in combination, a casing operatively associated with said member, an element rotatably mounted in said casing in engagement with said member and adapted to rotate in one direction or the other depending upon the direction of operation of said member, a switch mounted in said casing adjacent said element, an arm pivotally mounted in said casing in operative association with said switch and movable in one direction relative thereto to close said switch and in another direction to open said switch, said rotatable element comprising a clutch member, a second clutch member connected to said arm and engageable with said first-mentioned clutch member for moving said arm in switch closing direction upon rotation of said element in one direction and for opening said switch upon rotation of said element in the opposite direction, and spring means for forcing said second clutch member into engagement with said first clutch member.

30 10. A limit switch for a cyclically operating mechanism including a member operable in opposite directions for each cycle of operation of the mechanism, said switch comprising, in combination, a casing operatively associated with said member, an element rotatably mounted in said casing in engagement with said member and adapted to rotate in one direction or the other depending upon the direction of operation of said member, a switch mounted in said casing adj-

cent said element, an arm pivotally mounted in said casing in operative association with said switch and movable in one direction relative thereto to close said switch and in another direction to open said switch, said rotatable element comprising a clutch member, a second clutch member connected to said arm and engageable with said first-mentioned clutch member for moving said arm in switch closing direction upon rotation of said element in one direc-

tion and for opening said switch upon rotation of said element in the opposite direction, spring means for forcing said second clutch member into engagement with said first clutch member, and second spring means for constantly biasing said arm in switch opening direction whereby upon disengagement of said rotatable element with said movable member said last-mentioned spring means opens said switch.

10

JOHN D. STROBELL.
